UNITED STATES PATENT OFFICE.

JOHN L. SAUNDERS AND JESSE C. SAUNDERS, OF SEDALIA, MISSOURI, ASSIGNEES OF
ONE-HALF TO JOHN L. GUERRANT, OF SEDALIA, MISSOURI.

PERMUTATION LOCK.

Application filed November 16, 1922. Serial No. 601,270.

To all whom it may concern:

Be it known that we, JOHN L. SAUNDERS and JESSE C. SAUNDERS, citizens of United States, residing at Sedalia, in the county of

5 Pettis and State of Missouri, have invented certain new and useful Improvements in Permutation Locks, of which the following is a specification, reference being had therein to the accompanying drawing.

10 The present invention relates to permutation locks, and aims to provide such a lock comprising a novel construction and assemblage of the component elements to provide an advantageous and efficient lock.

15 A more specific object of the invention is the provision of a plurality of relatively rotatable tumblers or members assembled as a unit in a novel manner, which can be handled or manipulated as a unit without the 20 parts separating or falling apart.

Another object is the provision of a novel arrangement providing for changes in the combination under certain required conditions, and enabling such changes in combination to be made without separating the parts of the tumbler unit or device.

With the foregoing and other objects in view, which will be apparent as the description proceeds, the invention resides in the 30 construction and arrangement of parts, as hereinafter described and claimed, it being understood that changes can be made within the scope of what is claimed, without departing from the spirit of the invention.

35 The invention is illustrated in the accompanying drawings, wherein—

Figure 1 is a front view of one form of lock embodying the present improvements, and intended particularly as a car door or similar lock.

40 Fig. 2 is an enlarged vertical longitudinal section on the line 2—2 of Fig. 1, with the lock detached from its support.

Figs. 3 and 4 are cross or horizontal sections on the respective lines 3—3 and 4—4 of Fig. 2.

Fig. 5 is an elevation of the latch pin or spindle.

Fig. 6 is a sectional view similar to Fig. 2 showing the latch pin or spindle removed and replaced by a combination-changing key or member.

Fig. 7 is a cross or horizontal section taken on the line 7—7 of Fig. 6.

55 Fig. 8 is a median section of another form

of lock, portions being shown in elevation, the device being a padlock.

Fig. 9 is a section on the line 9—9 of Fig. 8.

Fig. 10 is an elevation of another modified form of lock, shown as a padlock, with the shackle open.

Fig. 11 is a median section of the padlock shown in Fig. 10, portions being shown in elevation, with the parts in locking position.

Fig. 12 is a median section of still another variation, showing the improvements incorporated in a lock for the steering column of a motor vehicle, portions being shown in elevation.

Referring to the first type of lock shown in Figs. 1 to 7, inclusive, which is intended particularly for use as a car door lock, or the like, and which is shown in a vertical position although it may be used in other

70 positions, there is provided a frame comprising the back plate 20 having the apertures 21 for fastening same to the car wall or other support. Said plate has the outstanding ears 22, 23, 24 and 25, and the ears 22, 23, and 24 have the apertures 26 through which the latch pin or spindle 28 is inserted, being moved downwardly through said ears with the lock in upright position as shown. The lower ear 25 has a socket 29 for receiving the lower end of the spindle 28, to protect same, and the hasp or other object to be held is engaged by the spindle between the ears 23 and 24, as seen in Fig.

1. The spindle 28 has a head 30 at its upper end to seat on the ear 22, and said spindle has an aperture 31 to be located between the ears 24 and 25 for receiving a seal, in order to prevent the latch pin or spindle being slid to open position without breaking the seal, even though the particular combination is known.

A hood or shield 32 is disposed above the plate 20 and spindle 28, for protecting the lock, and also limiting the upward movement of the spindle, in order to prevent the spindle being withdrawn from the tumbler device. The back of the hood 32 has an aperture 33 for securing it to the wall or support above the plate 20, and the end of the hood 32 adjacent to said plate has a lug 34 to extend between a pair of lugs 35 projecting from the upper end of the plate 20, thereby preventing the hood 32 from turning even though a single securing ele-

ment is used for fastening the hood to the support. The hood 32 and frame plate 20 are thus interengaged at their adjacent ends to prevent the hood from turning out of position. The hood 32 can be removed, however, when it is desired to withdraw the spindle 28 completely from the tumbler device, such as for the purpose of changing the combination, as will hereinafter more fully appear.

Disposed between the ears 22 and 23 of the frame is a set of rotatable tumblers of annular form, and designated 36, 37 and 38. These tumblers or rings 36, 37 and 38 are disposed end to end, or are superimposed in alinement or coaxial with one another, to register with the apertures 26 for the insertion of the spindle 28 through said tumblers or the sliding movement of said spindle when the tumblers are in set position. Each of the tumblers has a lug 39 projecting into the aperture thereof, and the spindle 28 has a longitudinal groove 40 and annular circumferential grooves 41, one for each lug 39, intersecting the groove 40. The ear 22 also has a lug 42 projecting into its aperture to engage in the groove 40, requiring the spindle 28 to be slid down in a predetermined angular position, and preventing said spindle from turning in the frame. When the spindle is slid home, as shown in Fig. 2, the grooves 41 are brought to common planes with the lugs 39, permitting the tumblers to be turned to move the lugs 39 into said grooves 41 away from the groove 40, thereby locking the spindle in place and preventing it from being slid open unless the tumblers are moved to "set" position with the lugs 39 in the line of the groove 40, as shown in Fig. 2.

The tumblers 36, 37 and 38 are assembled as a unit, to prevent them from being separated even when the tumbler device is removed from the frame, and the connections between the tumblers also provide for the free movements of the tumblers relatively to one another about their axes. The tumblers have interfitting portions. Thus, the tumblers 37 and 38 have the bosses or necks 43 entering recesses 44 in the respective tumblers 36 and 37, whereby the tumblers have portions fitted together telescopically. The overlapping portions of the tumblers have the confronting complementary annular grooves 45 in which the annular sets of balls 46 are disposed, whereby the balls provide anti-frictional connections between the tumblers, as well as securing the tumblers together against separation. The tumblers 36 and 37 have the apertures 47 extending from the corresponding grooves 45 to the outer periphery of said tumblers to enable the balls to be inserted and removed, and said apertures 47 are normally closed by the screw plugs 48 therein,

thereby retaining the balls in the grooves. The tumblers having the portions fitted together and provided with the grooves in which the balls are disposed, will enable the tumblers to turn freely relatively to one another, and the tumblers are also held assembled as a unit to be handled or manipulated without the tumblers falling apart. Thus, the tumbler unit or device, when removed from the frame, will remain intact, and the tumblers can only be separated by removing the screw plugs 48 and permitting the balls 46 to drop out through the apertures 47.

Index members are associated with the tumblers for setting the tumblers according to a predetermined combination, and, as shown, said members constitute the rings 49, 50 and 51 surrounding and fitted on the respective tumblers 36, 37 and 38, the rings 49 and 51 having the inturned annular flanges 51' overlapping the respective tumblers 36 and 38, whereby the rings or bands 49, 50 and 51 completely surround and enclose the tumblers. The index rings or members are used for turning the tumblers, and are capable of being set in different angular positions with reference to the corresponding tumblers, for changing the combination.

The combination changing means include the radial holding pins or members 52 slidably mounted in the tumblers 36, 37 and 38 and having their outer ends rounded to engage in the rounded notches or recesses 53 provided in the inner peripheries of the rings 49, 50 and 51. The inner ends of the pins 52 abut the spindle 28, preventing said pins from moving inwardly when the spindle is within the tumblers, and this retains the outer ends of the pins 52 in the corresponding notches 53. The rings 49, 50 and 51 have annular sets of notches 53 for the engagement of the pins 52, to change the combination. Coiled springs 54 surround the pins 52 and are confined between the flanges 55 on said pins and the shoulders 56 in the apertures with which the tumblers are provided, whereby the springs tend to move the pins 52 outwardly. As long as the spindle 28 is in place, the pins 52 are retained in the corresponding notches 53, so that each of the index rings and corresponding tumbler are compelled to turn one with the other. The rings 49, 50 and 51 being turned will therefore turn the tumblers accordingly.

A "click" means is provided for convenience in setting the tumblers with respect to one another. Thus, the intermediate ring 50 has an opening 58 extending therethrough parallel with its axis, and click members 59 are slidable in the ends of said opening 58 and are forced apart by means of a coiled spring 60 confined between said

members in said opening. The adjacent surfaces of the rings 49 and 51 have the annular series of notches or recesses 57 in which the rounded ends of the members 59 are arranged to snap, when the rings 49, 50 and 51 are rotated relatively to one another. The members 59 engaging in the notches 57 will serve to hold the rings in relative position with some frictional resistance, although said rings can be rotated relatively by forcing the members 59 out of the notches 57 by cam action, said members 59 being moved into the opening 58 and snapping into the notches 57 as the notches 57 and members 59 pass one another, as will be apparent.

The tumbler unit or device constituting the tumblers 36, 37 and 38 and the index rings 49, 50 and 51, with the elements between said tumblers and rings, fits snugly between the ears 22 and 23 of the frame, to prevent the tumbler unit from moving longitudinally of the spindle 28, but when the spindle is withdrawn, said tumbler unit or device can be removed from the frame, and the parts thereof are all held together. The rings 49, 50 and 51 are held on the tumblers by pins 52, although said rings can be stripped off, inasmuch as when the rings are pulled from the tumblers longitudinally of the axis of the tumblers, the pins 52 are forced inwardly, (this being permitted when the spindle 28 is removed). The plugs 48, which are normally covered and concealed by the rings 49 and 50 can now be removed for removing the balls 46, should it be desired to separate the tumblers.

In order to permit the spindle 28 to be slid to open position, the tumblers must be turned to a predetermined position relatively to one another and relatively to the frame. Thus, the tumblers are turned relatively to one another to bring certain markings thereon in alinement or registration, and the tumbler unit is then turned to bring such markings in registration or alinement with marks 61 on the ears 22 and 23, which will bring the lugs 39 in the line of the groove 40, so that the spindle 28 can be raised. When the spindle is moved down into place and the tumblers turned, this will destroy the combination, and the lock cannot be opened without the tumblers being set properly with a knowledge of the particular combination.

In changing the combination, the positions of the index rings with reference to the tumblers is altered. This can only be done with the assistance of a suitable combination-changing member or tool, which, as shown, comprises a pin 62 adapted to be slid down into the tumbler device, when the spindle 28 has been removed, the pin or member 62 having a longitudinal groove 63 corresponding with the groove 40 of the

spindle 28, for receiving the lugs 39 and 42. The lug 42 prevents the pin 62 from turning, and the lugs 39 engaging in the groove 63 will prevent the tumblers from turning. The pin 62 has a flat side 64 which confronts the pins 52, leaving a space or clearance behind said pins 52. This permits the pins 52 to be shoved inwardly by cam action when the rings 49, 50 and 51 are turned around the tumblers, and by changing the relative angular positions of said rings with reference to the tumblers, the combination can be changed within a wide latitude of combination changes. The pins 52 in being moved outwardly by the springs 54 will snap into the notches 53, and retain the rings in place on the tumblers. Then, the combination changing pin or member 62 is removed and the spindle 28 again inserted, and said spindle will then retain the pins 52 in the corresponding notches 53. Thus, in order to change the combination, the spindle 28 must be removed from within the tumblers, and a tool or member must be used for holding the tumblers against turning movement, and to permit the pins 52 to move inwardly when the index rings are turned relatively to the tumblers.

Figs. 8 and 9 illustrate the improvements as embodied in a padlock. The tumblers 36', 37' and 38' are swivelled together as a unit in substantially the same manner as hereinbefore disclosed, excepting that the bosses 43' are carried by the tumblers 36' and 38' and enter the intermediate tumbler 37'. The index rings 49', 50' and 51' are fitted on the tumblers and retained in the angular positions relatively to the tumblers by the pins or members 52' substantially the same as in the first form, the spindle 28' within the tumblers normally preventing the pins 52' from moving inwardly out of engagement with the index rings. An annular cap member 22' is fitted against the tumbler 36' and ring 49', and the member 22' and rings 49' and 50' have the annular lips 70 overlapping the corresponding tumblers 49', 50' and 51', to prevent the insertion of a prying implement between the parts in an effort to separate them. The spindle 28' has the longitudinal groove 40' and the annular circumferential grooves 41', whereby when the tumblers are turned to move the lugs 39' into the grooves 41' away from the groove 40', the spindle 28' is retained in place with the head 30' thereof in the recess 71 in the member 22'. The groove 40' terminates at its lower end short of the lower end of the spindle 28' at an annular circumferential groove 72 in the spindle adjacent to the lower end thereof, whereby when the spindle is raised, with the tumblers in set position, the lug 39' of the tumbler 38' will strike the lower end of the groove 40' and thus prevent the spin-

dle from being withdrawn. A slot or groove 73 extends from the groove 72 to the lower end of the spindle, whereby the tumbler 38' can be turned to move its lug 39' in the groove 72 to the slot 73, thereby permitting the tumbler 38' to be withdrawn from the spindle 28', bringing the lug 39' of the tumbler 37' to a position where it can be moved into the groove 72 for pulling the tumbler 37' from the spindle, in the same way that the tumbler 38' was removed, and the tumbler 36' can be removed in the same way. Thus, the tumblers can be removed from the spindle one at a time, without separating the tumblers. The tumbler 38' has a flange 23' retaining the ring 51' thereon, so that the index rings are retained between the flange 23' and the member 22' at the opposite ends of the tumbler unit, thereby preventing the index rings from being removed from the tumblers unless the tumblers are removed from the spindle 28'.

The member 22' is assembled with the tumbler 36' in the same manner that the tumblers are assembled with one another. Thus, the tumbler 36' has a boss 74 entering a recess 75 in the member 22', and said member and boss have the complementary annular grooves 76 in which balls 77 are disposed. The member 22' has an aperture 78 for the insertion of the balls extending to the grooves and normally closed by a screw plug 79, said plug and aperture being concealed underneath the head 30' of the spindle 28' when the lock is closed, thus preventing access being had to the plug 79 and balls 77 with the spindle 28' held within the tumblers by the lugs 39'.

A shackle 80 has one end 81 swivelled in the head or flange 30' of the spindle for turning movement. The other terminal of the shackle is adapted to seat sidewise in a notch 82 in the head or flange 30', and the member 22' has a complementary notch 83 to receive the free end of the shackle when said shackle is swung into the notch 82 and the spindle 28' moved into the tumblers to bring the head or flange 30' into the recess 71. The head 30' and free terminal of the shackle have the recess 84 and lug 85 to enter said recess when the shackle is swung into the notch 82, to prevent the free end of the shackle from being pried loose. Thus, with the parts in locking position, the shackle 80 is prevented from being swung laterally to open position, by seating in the notch 83 of the member 22', and the lug 85 engaging in the recess 84 will prevent the free terminal of the shackle being pried loose. By turning the tumblers to set the combination, with the lugs 39' in the line of the groove 40', the spindle 28' and tumblers can be separated a limited amount, thereby removing the head 30' and shackle from the recess 71, and the shackle can then be

swung laterally about the axis of the terminal 81.

It will be noted that, in this form of lock also, the tumblers are assembled as a unit, the balls between the tumblers holding them together without other assistance than the swivel joints between the tumblers themselves.

In order to change the combination, the spindle 28' is provided with recesses 64' with which the pins 52' register when the spindle 28' and tumblers are shifted lengthwise relatively to one another to a predetermined position, with the lugs 39' in the groove 40'. Then, by holding the spindle and tumblers in such relative longitudinal position, the index rings 49', 50' and 51' can be turned on the tumblers, the pins 52' being moved into the recesses 64'. The combination can only be changed, however, when the combination is known and the spindle and tumblers separated slightly to bring the recesses 64' behind the pins 52'.

Another type of padlock is shown in Figs. 10 and 11, and includes the tumblers 36'', 37'' and 38'' swivelled together in substantially the same manner as shown in Figs. 2, 4 and 6, with the balls 46'' retaining the tumblers assembled. The index rings 49'', 50'' and 51'' are retained in position on the tumblers by the pins or members 52'' in the same manner as shown in Figs. 2, 3 and 8, and the spindle 28'' on which the tumblers are fitted has the recesses 64'' to receive the pins 52'' in a predetermined relative longitudinal position of the tumblers and spindle, for changing the combination, the same as with the padlock shown in Fig. 8. A cap member 22'' is connected to the tumbler 36'' by a swivel connection including the balls 77'' between them, the same as between the parts 36' and 22' in Fig. 8, excepting that the screw plug 79'' extends to the edge or margin of the member 22''. The index rings are retained between the flange 23'' on the tumbler 38'' and the member 22'', and even though the screw plug 79'' can be removed, to separate the member 22'' and tumblers, this will not enable the lock to be opened because the short limb of the shackle 80'' also enters the tumbler 36'' when the lock is in closed position as shown in Fig. 11. In this form, the same as in the form shown in Fig. 8, the tumblers are held assembled by the swivel joints between them, and the parts of the tumbler unit or device move one with the other on the spindle. The spindle 28'' has a base 86 in which the terminal of the long limb of the shackle 80'' is swivelled for turning movement, as at 81'', whereby when the tumblers are set so that the lugs 39'' thereof can move down in the groove 40'', the short or free limb of the shackle can be swung open, as seen in Fig. 10. The member 28'' has an extension 130

87 slidable on the long limb of the shackle, and the member 22" also has a stop 88 at the aperture thereof against which the free end of the shackle strikes when the shackle is moved or swung to a position to enter the tumbler unit or device when said unit or device is raised to the position shown in Fig. 11.

The spindle 28" is also provided with the 10 groove 72" and slot 73" at the upper end thereof to permit the tumblers to be removed from the spindle one at a time by turning them so that their lugs 39' can enter the groove 72" and pass out through the slot 15 73", but this can only be done when the member 22' is detached from the tumbler 36" and the member 22" swung with the shackle out of the way.

Fig. 12 shows the improvements as embodied in a lock disposed on the steering column of a motor vehicle. The tubular steering column is indicated at 28^a, which takes the place of the spindles in the other forms of locks, said column 28^a being provided 25 with the longitudinal groove 40^a and the annular circumferential grooves 41^a for the reception of the lugs 39^a of the tumblers 36^a, 37^a and 38^a. The tumblers are swivelled together by balls 46^a, the same as in the other 30 forms, and the index rings 49^a, 50^a and 51^a are retained in position on the tumblers by the pins or members 52^a which abut the column or post 28^a to prevent the combination being changed unless the tumbler unit or device 35 is shifted longitudinally on the column to bring the pins 52^a in alinement with the recesses 64^a in the column, the same as in the forms shown in Figs. 8 and 11. A collar 22^a slidable on the steering column has 40 a swivel connection with the tumbler 36^a by means of the balls 77^a, the same as shown in Fig. 11 between the members 22" and 36" with the screw plug 79^a extending to the circumference of said collar. The index 45 rings or bands are held on the tumblers between the flange or shoulder 23^a on the tumbler 38^a and the collar 22^a, and the tumblers, index rings and collar are slidable as a unit and constitute a locking sleeve on the steering 50 column.

A latch 90 is slidable radially in the column or post 28^a to enter a recess or socket 91 in the steering shaft 92 which extends through the column, the steering wheel 93 being secured on the shaft at the upper end of the column. The latch 90 has a head 94 at its outer end and a coil spring 95 surrounds the latch and is confined between said head 94 and a shoulder 96, thereby 55 tending to retract the latch from the shaft 92. The collar 22^a has a cam slot 97 extending longitudinally at the inner periphery thereof and receiving the head 94 of the latch 90, whereby when the locking sleeve is 60 slid upwardly on the steering column to

locking position, with the lugs 39^a movable in the grooves 41^a, the latch 90 is forced inwardly to enter the recess 91 and thereby prevent the shaft 92 from being turned, which will avoid the vehicle being steered, in 70 order to prevent the theft thereof. When the tumblers are set so that the lugs 39^a thereof can move in the slot or groove 40^a, the locking sleeve can be slid downwardly, 75 permitting the spring 95 to retract the latch 90, so that the shaft 92 can be turned for steering the vehicle.

The combination can be changed when the tumblers are slid to a certain position to bring the pins or members 52^a in registration with the recesses 64^a, and the lock can be removed from the column by first removing the hand wheel 93 from the shaft 92, then detaching the collar 22^a from the tumbler 36^a and removing the latch 90. The 80 tumbler unit or device can then be slipped off of the column.

This application is in part a continuation of two previous applications, one filed March 21, 1921, Serial No. 454,076 and the other filed September 19, 1921, Serial No. 501,520, the present disclosure containing some changes and improvements as over the disclosures in said applications, although such 90 applications disclose substantially the same principles in the swivelled connections between the tumblers and the combination changing means.

Having thus described the invention, what 100 is claimed as new is:

1. In a lock, tumblers adapted to be turned relatively to one another and having portions fitted together telescopically in overlapping relation, said portions having complementary annular grooves, and means in 105 said grooves holding the tumblers assembled as a unit and preventing the separation of the tumblers until after said means are removed from said grooves.

2. In a lock, tumblers adapted to be 110 turned relatively to one another and having portions fitted together telescopically in overlapping relation, said overlapping portions having complementary annular grooves, and means in said grooves holding the tumblers assembled as a unit and removable from between said grooves while the tumblers are assembled, to permit the tumblers to be separated.

3. In a lock, tumblers adapted to be 115 turned relatively to one another and having portions fitted together in overlapping relation, the overlapping portions having complementary annular grooves, and balls in said grooves holding the tumblers assembled 120 as a unit.

4. In a lock, tumblers adapted to be 125 turned relatively to one another and having portions fitted together and grooved, means in the grooved portions for holding the tum- 130

blers assembled, one tumbler having an aperture extending to the grooved portion for the passage of said means into and out of the grooved portion, and means for closing said aperture.

5. In a lock, tumblers adapted to be turned relatively to one another and having portions fitted together and formed with complementary grooves, balls in said grooves 10 for holding the tumblers assembled, one tumbler having an aperture for the passage of the balls, and means for closing said aperture.

6. In a lock, tumblers adapted to be turned relatively to one another and having portions fitted together, means cooperable with said portions for holding the tumblers assembled with a swivel connection and removable from said portions, and index members 20 on the tumblers preventing access to said means.

7. In a lock, tumblers adapted to be turned relatively to one another and having portions fitted together, means between said 25 portions for holding the tumblers assembled with a swivel connection, one tumbler having an aperture for the removal of said means, and an index member fitted on said tumbler over said aperture.

30 8. In a lock, tumblers adapted to be turned relatively to one another and having portions fitted together and provided with complementary grooves, balls in said grooves, one tumbler having an aperture for the passage of the balls, and a member fitted on said tumbler across said aperture.

9. In a lock, annular rotatable tumblers having portions fitted together and provided with complementary grooves, balls in said 40 grooves holding the tumblers assembled, one tumbler having an aperture for the passage of the balls and extending to the outer periphery of said tumbler, and a ring fitted around said tumbler.

45 10. In a lock, a tumbler, a member with which the tumbler is engageable in the locking position of said tumbler, an index member on the tumbler for moving it to unlock- 50 ing position and adapted to be set in different positions relatively to the tumbler while assembled with the tumbler, and means between said tumbler and index member movable into and out of engagement with one of them and cooperable with the first- 55 named member to prevent the disengagement of said means when the tumbler and first-named member are in locking position.

60 11. In a lock, a tumbler, a member with which the tumbler is engageable when they are in locking position, an index member on the tumbler adjustable to different positions relatively to the tumbler while said index member and tumbler are assembled, and means carried by the tumbler engageable 65 with and disengageable from the index mem-

ber while the index member and tumbler are assembled, said means being cooperable with the firstnamed member to prevent said means being disengaged from the index member when the tumbler and the firstnamed member are in locking position.

70 12. In a lock, a tumbler, a member with which the tumbler is engageable when said member and tumbler are in locking position, an index member fitted on the tumbler and movable to different positions relatively to the tumbler while they are assembled, said index member having a series of notches, and a holding member movable in the tumbler to engage in said notches for moving the tumbler with the index member, said holding member being cooperable with the firstnamed member to prevent said holding member being disengaged from the corresponding notch when the firstnamed member and tumbler are in locking position.

75 13. In a lock, a tumbler, a member with which the tumbler is engageable when the tumbler and member are in locking position, an index member fitted on the tumbler and adjustable to different positions relatively to the tumbler while they are assembled, said index member having a series of notches, and a holding member movable in the tumbler to engage in said notches for moving the tumbler with the index member, said holding member being arranged to abut the firstnamed member when said firstnamed member and tumbler are in locking position to prevent said holding member being disengaged from the corresponding notch.

80 14. In a lock, a tumbler, a member to be engaged by the tumbler when said member and tumbler are in locking position, an index member fitted on the tumbler and adapted to be adjusted to different positions relatively to the tumbler while they are assembled, said index member having a series of notches, a holding member movable in the tumbler to engage in said notches, and spring means between said holding member and tumbler for moving the holding member to engage in said notches, said holding member being arranged to be prevented, by the firstnamed member, from disengaging the corresponding notch when the firstnamed member and tumbler are in locking position.

85 15. In a lock, a member, an annular tumbler to surround said member and having means to engage said member when said member and tumbler are in locking position, an index ring fitted on and surrounding said tumbler and adapted to be turned to different angular positions relatively to the tumbler while said tumbler and ring are assembled, and holding means between said ring and tumbler movable into and out of engagement with one of them, said holding means being arranged so as to prevent the 90 100 105 110 115 120 125 130

disengagement thereof, by the firstnamed member, when said firstnamed member and tumbler are in locking position.

16. In a lock, a member, an annular tumbler to be disposed thereon having means to engage said member when said member and tumbler are in locking position, an index ring fitted on and surrounding said tumbler and adapted to be turned to different angular positions relatively to the tumbler while the tumbler and ring are assembled, and a holding member movable in the tumbler to engage the ring for turning the tumbler with the ring and cooperable with the firstnamed member to prevent the holding member from disengaging said ring when said tumbler and member are in locking position.

17. In a lock, a member, an annular tumbler to be disposed thereon having means to engage said member when they are in locking position, an index ring fitted on and surrounding said tumbler and having a series of notches, and a holding member movable in the tumbler to engage in said notches for turning the tumbler with said ring, said holding member being arranged to abut the firstnamed member when the tumbler and firstnamed member are in locking position to prevent the holding member from being disengaged from the corresponding notch of the ring.

18. In a lock, a member, an annular tumbler to be disposed thereon having means to engage said member when they are in

locking position, an index ring fitted on and surrounding said tumbler and having a series of notches therein, a holding member slideable in the tumbler and having its outer end formed to snap into and out of said notches, and spring means between said holding member and tumbler for moving the holding member outwardly to engage in said notches, said holding member abutting, at its inner end, the firstnamed member when the firstnamed member and tumbler are in locking position to prevent the outer end of said holding member being removed from the corresponding notch of the ring.

19. In a lock, an annular tumbler to fit around a member, an index ring fitted on and surrounding said tumbler and having a series of notches therein, and a holding member slideable in the tumbler and engageable at one end in said notches for turning the tumbler with said ring, the other end of the holding member being projectable into the opening of the tumbler to disengage the holding member from said notches so as to prevent the disengagement of the holding member from said notches when the tumbler is on the firstnamed member with the holding member abutting said firstnamed member.

In testimony whereof we hereunto affix our signatures.

JOHN L. SAUNDERS.
